UNITED STATES PATENT OFFICE.

GEORGE M. URIE, OF KANSAS CITY, MISSOURI, ASSIGNOR TO REGINALD B. CALCUTT,
OF CHICAGO, ILLINOIS.

OIL DUSTER AND POLISHER.

1,089,732.

Specification of Letters Patent. Patented Mar. 10, 1914.

Application filed January 31, 1912. Serial No. 874,468.

To all whom it may concern:

Be it known that I, GEORGE M. URIE, a citizen of the United States, residing at Kansas City, in the State of Missouri, have 5 invented certain new and useful Improvements in Oil Dusters and Polishers, of which the following is a specification.

This invention relates to an improved oil polisher and dust absorber, and has for its 10 object to provide a combined polisher and dust absorber.

With the foregoing and other objects in view, the invention consists in the novel features of construction, combination and arrangement of parts illustrated in the drawings and more particularly pointed out in the appended claims.

In the accompanying drawings:—Figure 1 is a side elevation of a device of the character specified embodying my improvements. Fig. 2 is a plan view thereof. Fig. 3 is a central vertical section, taken on line 3—3 of Fig. 1, with the parts represented on an enlarged scale. Fig. 4 is a plan view of the 25 cleaning and polishing surface unattached and unfolded. Fig. 5 is a view similar to Fig. 1 of a modified form of the device. Fig. 6 is a vertical transverse section, taken on line 6—6 of Fig. 5, the parts shown on an enlarged scale. Fig. 7 is a side elevation of another modified form of the device, and Fig. 8 is a central vertical section taken on line 8—8 of Fig. 7, with the parts represented on an enlarged scale.

Referring to the drawings for a more particular description of the device, and which drawings are for illustrative purposes only and are therefore not drawn to scale, the device comprises the cylindrical head 1, preferably constructed of wood, and formed with the concave outer edge 2, the handle 3, connected with the head by the attaching and clamping ring 4, and the cleaning and polishing material or element 5.

In the preferred form of the device, illustrated in Figs. 1 to 3, inclusive, the ring 4 not only provides a means of attaching the handle to the head but also acts to clamp the duster around the outer edge of the latter. The ends of the wire forming the ring are twisted together, as at 6, and screw into a corresponding socket, as 7, in the inner end of the handle.

The duster is constructed of cotton warp 55 fibers folded at the center, as indicated, and

the outer and inner strips of sheeting 8 and 9, respectively. The strips of sheeting and cotton fibers are stitched together at 10 and 11, respectively, the stitching running entirely around the wooden head. By this means the top of the duster, that is, that portion encircling the head 1, is bound together and held rigid, while the cotton warp fibers extending below the head are loose and flexible to form the cleaning and polishing surface.

In the preferred form of the device, the rigid part of the duster is secured to the head by the clamping ring, which encircles the former.

In the modified form of construction, shown in Figs. 5 and 6, the rigid part of the duster is fastened to the head by the nails 12 which pass transversely therethrough and penetrate the edge of the head. In this 75 form, the ring encircles the edge of the head and merely serves as an attaching medium for the handle.

In the modified form of construction shown in Figs. 7 and 8, the head 1 is eliminated and the ring fits between the folds 13 and 14 of the rigid part of the duster.

As shown in the drawings, the edges of the outer strip of sheeting are folded in, as at 15, and stitched to the inner and outer 85 layers of the duster.

In practice, the bottom flexible portion of the duster is saturated with solid oil of cedar wood and cedar leaves, which absorbs all dust on the furniture or floor or other wood-work and at the same times polishes the same. In this connection it may be said that it has been found that the solid oil of cedar wood and cedar leaves effectually destroys all manner of insect life, and the device therefore also serves the purpose of an insecticide.

The device is especially constructed to absorb a quantity of oil of cedar wood and cedar leaves and to apply the oil thus absorbed in the most effective manner.

From the foregoing description taken in connection with the drawings, it is thought that the construction, purpose and advantages of this invention will be readily understood without requiring a more extended explanation.

Various changes in the form, proportions and minor details of construction may be resorted to without departing from the prin- 110

ciples or sacrificing any of the advantages of this invention as defined in the appended claims.

Having described my invention, what I claim as new, is:—

1. A device of the class specified comprising a cylindrical disk-shaped head provided with a concave outer edge, a mop constructed of cotton warp fibers folded together with the folded portions of the fibers encircling the outer concave edge of the head and stitched together, the ends of the fibers extending beneath the head and constituting a soft flexible absorptive cleaning and polishing surface, an inner strip of sheeting between the layers of the folded portion of the mop, an outer strip of sheeting, covering the outer and inner edges of the folded portion of the mop with said outer and inner strips stitched to said folded portion, a handle, means for attaching the handle to the head and means for holding the folded portion of the mop on the head.
2. A device of the class specified comprising a mop consisting of cotton warp fibers folded together with the ends of the fibers extending beneath the folded portion and constituting a soft flexible absorptive cleaning and polishing surface, an inner strip of sheeting between the layers of the folded portion of the mop, an outer strip of sheeting covering the outer and inner edges of the folded portion of the mop with said outer

and inner strips stitched to said folded portion, a handle and means to which said mop is attached comprising a ring formed from a single piece of wire with its ends twisted together in the form of a spiral screw adapted to screw into the inner end of the handle.

3. A device of the kind specified comprising a suitable handle, a substantially flat plate removably carried thereby, and having a substantially continuous concave channel in the edge thereof, and a removable mop having a reinforced upper portion that encircles said plate and is seated in said channel and is confined and secured therein.

4. A device of the class specified comprising a mop consisting of cotton warp fibers folded together with the ends of the fibers extending beneath the folded portion and constituting a soft flexible absorptive cleaning and polishing surface, an inner strip of sheeting between the layers of the folded portion of the mop, an outer strip of sheeting covering the outer and inner edges of the folded portion of the mop with said outer and inner strips stitched to said folded portion, a handle and means to which said mop is attached which includes a ring.

In testimony whereof I affix my signature in presence of two witnesses.

GEORGE M. URIE.
